UNITED STATES PATENT OFFICE.

EDGAR B. HIATT, OF PALISADE, COLORADO.

BASKET LINER.

Application filed January 22, 1926. Serial No. 33,352.

This invention relates to certain improvements in basket liners and has relation more particularly to a device of this kind especially adapted for use in connection with baskets adapted to be filled with fruit and the like, and which serves to provide an effectual medium to protect the contents of the basket from injury by direct contact with the wall of the basket.

10 It is an object of the invention to provide a liner of this kind which is adapted to substantially snugly fit within a basket and which has its wall endless or continuous, said wall being preferably weak so that it can be collapsed to occupy a minimum of space in shipment, such collapsing of the liner permitting the same to be conveniently transported in packages.

Another object of the invention is to provide a liner of this kind consisting of a weak endless wall possessing initially sufficient inherent strength to hold a column of fruit or the like, without any independent support, before being applied within a basket and wherein the wall of the liner is of sufficient weakness to render it susceptible of yielding at any point under the internal pressure of the fruit within it to permit the liner to compensate for any irregularities which may be in the inner wall of the basket.

The invention consists in the details of construction and in the combination and arrangement of the several parts of my improved basket liner whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in side elevation and partly in section illustrating a liner constructed in accordance with an embodiment of my invention applied within an upended basket;

Figure 2 is a view in perspective of my improved liner as herein disclosed;

Figure 3 is a view in plan illustrating a blank from which the liner is produced.

As disclosed in the accompanying draw-

ings, L denotes a liner constructed in accordance with an embodiment of my invention and which comprises a sheet of material such as cardboard or kindred material which will permit the liner to have what may be termed a weak wall. This liner is open at its top and bottom and has its wall continuous or endless, such construction of the wall being accomplished by overlapping, as at 1, the ends of the blank from which the liner is formed and securing said overlapping extremities one to the other by cement or any other means which can be employed to advantage.

The blank when initially cut has its longitudinal edges each disposed on a curvature of a radius determined by the size of the basket in which it is to be applied and the lower of such edges is of a length less than that of the opposite longitudinal edge so that when the liner is in complete formation it is substantially in the form of a truncated cone so that the liner will substantially conform to the interior peripheral configuration of the basket.

It is of utmost importance to have the wall of the liner continuous or annular as by so doing it permits a liner to be filled with fruit or the like and hold such column before it is properly associated with the basket in accordance with the method and apparatus for packing fruit or the like as described and claimed in my Patent No. 1,578,341 dated February 16, 1926.

The liner is also preferably of such dimensions to extend a distance above the rim or top of the basket in which it is applied so that it effectively protects the contents of the basket or more particularly what may be termed the top layer coming in contact with the top basket rim R or with the rim of the applied basket lid B.

I also find it of advantage to provide the wall of the liner with the openings or perforations 2 whereby requisite circulation of air is permitted through the contents of the basket to prevent deterioration thereof which would have a tendency to occur without the provision of such openings.

The wall of the liner at substantially diametrically opposed points may be provided thereacross with the scored lines 3 to additionally weaken the wall at such points so that the container may readily collapse into a flattened condition to facilitate shipment in packages.

The wall of the liner L is initially of such strength to maintain the fruit or other content in requisite column and especially during the period the basket A is being applied thereto and particularly in accordance with the disclosure in my patent hereinbefore referred to. This liner is also of a size to receive substantially the full content of the basket to be filled. After the basket and its content has been suspended and is subjected to a shaking or jolting action to cause the fruit or the like to settle within the basket, the wall of the liner L will readily yield and fracture or break, as indicated at a to compensate for irregularities in the inner wall of the basket and assure the most effective compacting of the basket content so as to permit the stress or pressure of the content to be received directly upon the wall of the basket.

This application is partly in continuation of my application Serial No. 39,113 filed June 23, 1925.

From the foregoing description it is thought to be obvious that a basket liner constructed in accordance with my invention is particularly well adapted for use by

reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

As a new article of manufacture, a basket liner for use in packing fruit consisting of a weak endless wall, said wall initially possessing sufficient inherent strength to hold a column of fruit without any independent support before being applied within a basket, but of sufficient weakness to render it susceptible of yielding outward at any point under the pressure of the contents to permit it to compensate for irregularities in the inner wall of the basket.

In testimony whereof I hereunto affix my signature.

ENOS B. HIATT.

The wall of the liner L is initially of such strength to maintain the fruit or other content in requisite column and especially during the period the basket A is being applied thereto and particularly in accordance with the disclosure in my patent hereinbefore referred to. This liner is also of a size to receive substantially the full content of the basket to be filled. After the basket and its content has been up-ended and is subjected to a shaking or jolting action to cause the fruit or the like to settle within the basket, the wall of the liner L will readily yield and fracture or break, as indicated at a to compensate for irregularities in the inner wall of the basket and assure the most effective compacting of the basket content so as to permit the stress or pressure of the content to be received directly upon the wall of the basket.

This application is partly in continuation of my application Serial No. 39,113 filed June 23, 1925.

From the foregoing description it is thought to be obvious that a basket liner constructed in accordance with my invention is particularly well adapted for use by

reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

As a new article of manufacture, a basket liner for use in packing fruit consisting of a weak endless wall, said wall initially possessing sufficient inherent strength to hold a column of fruit without any independent support before being applied within a basket, but of sufficient weakness to render it susceptible of yielding outward at any point under the pressure of the contents to permit it to compensate for irregularities in the inner wall of the basket.

In testimony whereof I hereunto affix my signature.

ENOS B. HIATT.

DISCLAIMER

1,593,302.—*Enos B. Hiatt, Palisade, Colo. BASKET LINER. Patent dated July 20, 1926. Disclaimer filed May 31, 1932, by the assignee, Carpenter-Hiatt Sales Company.*

Hereby disclaims any basket liner for use in packing fruit as described in the said claim, except a liner which is of sufficient weakness to render it susceptible of yielding to the extent of fracturing or breaking outwardly under the conditions stated in said claim.

[Official Gazette July 5, 1932.]

DISCLAIMER

1,593,302.—*Enos B. Hiatt*, Palisade, Colo. BASKET LINER. Patent dated July 20, 1926. Disclaimer filed May 31, 1932, by the assignee, *Carpenter-Hiatt Sales Company*.

Hereby disclaims any basket liner for use in packing fruit as described in the said claim, except a liner which is of sufficient weakness to render it susceptible of yielding to the extent of fracturing or breaking outwardly under the conditions stated in said claim.
